INTEROFFICE CONNECTION

Karl L. Burgener, Villa Park, Ill., assignor to Automatic Electric Laboratories, Inc., Chicago, Ill., a corporation of Delaware

Application September 15, 1945, Serial No. 616,617

24 Claims. (Cl. 129—27)

1

This invention relates to telephone systems in general and more particularly to improved arrangements for interconnecting automatic offices with other offices through operator attended switchboards.

It is an object of this invention to provide improved means for completing connections between an automatic exchange and another exchange.

It is another object of this invention to provide improved arrangements for completing inter-office connections for subscribers in an automatic office by means of automatic switches controlled either through an operator attended switchboard in the automatic office or controlled through an operator attended switchboard in a distant office.

It is a further object of this invention to provide a novel arrangement whereby the seizure of a trunk circuit at one office will either operate a signal at an operator attended switchboard in an automatic office or seize an automatic switch in the automatic office.

It is a still further object of this invention to provide a novel arrangement whereby the seizure of a trunk circuit at an automatic office will either operate a signal at an operator attended switchboard in the automatic office or operate a signal in an operator attended switchboard in another office.

A particular feature of this invention is the provision of manually controlled switching means in the trunk circuit at the automatic office so that calls from another office may be directed either to an operator attended switchboard at the automatic office or to an automatic switch thereat, and so that calls from the automatic office may be directed either to an operator attended switchboard at the automatic office or to an operator attended switchboard at another office.

Another feature of the invention is that directionally controlled current flows over the trunk conductors during the progress of calls directed to the automatic office and that current flows over the trunk conductors only during signalling when calls are directed from the automatic office to another office.

A further feature of the invention is that two trunk conductors are used for operating the line signal at the automatic office when calls are directed to the automatic office and that one conductor is used to operate the line signal at another office when calls are directed thereto from the automatic office.

Another feature of the invention is that the line relay of the trunk circuit at the automatic

2

office operates on calls directed to the automatic office to operate the line signal and also operates on calls directed to another office to control supervisory signals.

5. Another feature of the invention is that a bridge across the trunk conductors at the distant end of the trunk is effective for seizing and controlling the trunk circuit on calls directed to the automatic office and that a bridge across the 10 trunk conductors at the distant end of the trunk is ineffective until the automatic office disconnects when calls are directed from the automatic office to another office.

The above features and others not particularly 15 mentioned at this time will be described in detail in the following specification with the aid of the accompanying drawings comprising Figs. 1, 2, 3 and 4.

Figs. 1 and 2 illustrate an automatic exchange, 20 an attendants switchboard, and a two way trunk circuit for connection to a distant switchboard.

Fig. 3 illustrates a cord circuit and associated equipment suitable for connection to the two way trunk circuit shown in Fig. 2.

Fig. 4 illustrates operators' common equipment for use with the cord circuit in Fig. 3.

Fig. 1 diagrammatically illustrates an automatic telephone exchange comprising subscribers' lines, three of which are shown at 1, 2 and 3, equipped with subscribers' substations, as shown at A, B and C respectively, line switches included in line switch units, one of which is shown at LSU; connector switches, one of which is shown at CONN; selector switches, one of which is shown at SEL, lineswitches, one of which is shown at LS, and part of an operator attended switchboard X comprising incoming trunks, such as trunk D; outgoing trunks such as trunk E; connecting links equipped with connecting keys such as keys 160 and 170; talk keys such as key 199; and supervisory lamps such as lamp 181; an operator's telephone shown at G; an auxiliary signal circuit shown at F; and a calling device shown at H. The switchboard X is equipped with two way trunks such as trunk J; Fig. 2, which are associated with the connecting links by connecting keys such as key 260 and supervisory lamps such as lamp 271. Trunk J is associated with incoming trunks such as trunk D and outgoing trunks such as trunk E through switching keys such as key 265.

The equipment shown in the dotted enclosure of Fig. 2 illustrates the terminating equipment at a distant switchboard Y for trunk circuits such as trunk J. Fig. 3 shows a cord circuit K at switchboard Y suitable for establishing connection over

trunk circuits such as trunk J. The switchboard Y is equipped with a plurality of cord circuits such as cord circuit K, and a plurality of terminating circuits for lines one of which is shown at N and is suitable for use as a common battery line, another, shown at P, is suitable for use as a magneto or toll line, and still another, shown at R, is suitable for connection to an automatic switchboard for outgoing service. The lines N and P can be connected to a subscriber's substation or other equipment suitable for use thereon over the conductors N¹ and N² and P¹ and P² respectively. The line R can be terminated on an automatic switch which may be a line switch, a selector or a connector similar to those shown on Fig. 1. The switchboard Y may have more than one operator's position in which case the terminating equipment for trunk circuit J and line circuits N, P, and R will be multiplied throughout the board so that it is accessible to each operator's position. The cord circuits, such as cord K, in a position are arranged for connection to operator's equipment common to the position as shown in Fig. 4, comprising an operator's telephone M, a calling device S and other apparatus which cooperates with the apparatus in the cord circuits, such as cord circuit K, and enables the operator to perform the necessary operations for establishing connections.

The subscribers' lines, such as line I in Fig. 1, extend between subscribers' substations such as substation A and line switches in units such as LSU, and are multiplied to connectors, such as the connector CONN. The line switches included in the units LSU may be of any desired type although preferably they are of the plunger or rotary type having their banks multiplied together in groups and connected over trunk lines such as that indicated at 4 to selector switches such as the selector SEL.

The selectors, such as SEL are preferably of the well known Strowger type such as described in Patent 2,189,400, granted February 6, 1940, to Clarence E. Lomax and Pier Bakker, and are accessible to the line switches in the units LSU and also to the line switches such as LS which are associated with outgoing trunks such as trunk E. The selectors have access to connectors, such as connector CONN, and to incoming trunks, such as trunk D.

The connectors, such as connector CONN, are preferably of the well known Strowger vertical and rotary type such as described in Patent 2,040,153, granted May 12, 1936, to Seth Peterson, and have access to subscribers' lines such as the line I. In the present case connectors, such as CONN, are accessible to calling subscribers, such as the subscriber at substation A, by way of their individual lines, such as line I, their individual line switches in units such as LSU, trunk lines such as that indicated at 4, and selectors such as SEL. The connector CONN is arranged to test a line to which it has been connected to determine whether the line is busy or free. If the line is busy the connector returns a distinctive tone, commonly known as busy tone, to the calling line. If the line is free the connector automatically signals the called line and returns a distinctive tone, commonly known as ring back tone to the calling line.

The line switches, selectors and connectors are controlled by subscribers by means of substations, such as A, which are equipped with calling devices and permit subscribers to establish connections directly with subscribers at substations such

as B. The operation of the automatic switches when used for establishing connections between subscriber lines is well known and does not form a part of this invention. It will, therefore, not be described.

The incoming trunks, such as trunk D, are associated with an operator attended switchboard X where they terminate on connecting keys, such as the key 140, in connecting link circuits. While only one connecting key 140 is shown an identical key is provided for the trunk D in each connecting link and the leads of the trunk are multiplied to each of the keys. The line lamp 182 is a part of the incoming trunk D and is lighted when the trunk has been seized by a selector, such as SEL, to signal the operator. The switchboard X is accessible to subscribers' substations such as substation A, by way of the line switch in unit LSU individual to the line I, selectors such as SEL, and incoming trunks such as D. The incoming trunk D is also connected to the two way trunk circuit J, Fig. 2, and to the line switch LS by means of the key 265 and the relay 210. The operation of the key 265 which is preferably mounted in the switchboard will automatically extend calls routed to the trunk D to the two way trunk J and will light the lamp 295 associated with terminating equipment for the trunk J at switchboard Y. The connection to the line switch LS through spring 266 and lead 15 prevents interference by the line switch with calls automatically extended from trunk D to trunk J.

There is a plurality of incoming trunks such as D in the switchboard X, each trunk having a connecting key such as key 140 in each of the links, and each trunk having a line lamp such as lamp 182.

The outgoing trunks, such as trunk E, are associated with the switchboard X where they terminate on connecting keys, such as key 170. An identical key is provided for trunk E in each connecting link and the trunk leads are multiplied to each of the keys. The outgoing trunks extend to line switches, such as line switch LS, which is identical to the line switches in the units LSU and may be in one of the LSU units. The line switches, such as LS, have access to the selectors, such as SEL, and through the selectors and connectors, such as connector CONN, to subscriber substations such as substation A. A calling device H can be connected to the outgoing trunks through a dialing key such as key 160. The outgoing trunks thus make subscribers' substations, such as substation A, accessible to the switchboard X. The outgoing trunk E is also connected to the two way trunk J, Fig. 2, by means of the key 265. The operation of the key 265 automatically extends calls routed from switchboard Y over trunk J to one of the selectors, such as selector SEL, by means of the line switch LS. The connection from the line switch LS over lead 15 and spring 266 to the trunk D prevents interference by the trunk D with connections automatically extended from trunk J to a selector such as SEL.

There is a plurality of outgoing trunks such as E in the switchboard X, each trunk having a connecting key such as key 170 in each of the links, and each trunk having a dialing key such as key 160 and extending to a line switch such as the line switch LS.

The two way trunks such as trunk J terminate on connecting keys such as key 260. An identical key is provided for trunk J in each connecting link and the trunk leads are multiplied to each

key. The trunks extend over conductors such as 40 and 41 to a distant switchboard where they terminate on jacks such as jack 290. The line lamp 272 is part of the two way trunk J and, in case key 265 is normal, is lighted when the trunk J is seized at switchboard Y to signal the operator at switchboard X. The guard lamp 273 is also part of the trunk J and is lighted after the operator at switchboard X disconnects, by restoring the connecting key, such as key 260, and remains lighted until the trunk J is released at the switchboard Y. The two way trunk J is connected to outgoing trunk E and to incoming trunk D by means of the key 265 and the relay 210. The operation of the key 265 automatically extends connections originating at the switchboard Y and routed over trunk J, to selectors, such as SEL, by means of the line switch LS and automatically extends calls routed from selectors to incoming trunk D over trunk J to the switchboard Y. The two way trunks are equipped with line lamps, such as lamp 295, at switchboard Y which are lighted to signal the operator thereat, when connections are routed either from switchboard X or from selectors such as SEL over the two way trunks to switchboard Y.

There is a plurality of two way trunks such as trunk J in the switchboard X, each trunk having a connecting key such as key 260 in each link, and each trunk having a line lamp such as lamp 272, a guard lamp such as lamp 273, and a switching key such as key 265. The switching keys, such as key 265, associate each of the two way trunks with individual ones of the incoming trunks such as trunk D and with individual ones of the outgoing trunks such as trunk E. At the switchboard Y each two way trunk terminates on a jack, such as jack 290, and is equipped with a line lamp such as lamp 295. If the switchboard Y has more than one operator's position the jack 290 and the lamp 295 are multiplied to other identical jacks and lamps which are distributed throughout the switchboard so that each operator will have access to the two way trunks by means of cord circuits such as cord K.

The link circuits in the switchboard X have connecting keys such as the key 140 for each incoming trunk, such as trunk D, in each link, connecting keys such as the key 170 for each outgoing trunk, such as trunk E, in each link and connecting keys such as the key 260 for each two way trunk, such as trunk J, in each link, and a talk key such as key 190, a local supervisory lamp, such as lamp 181, and a trunk supervisory lamp, such as 271 in each link. Leads such as 27 and 28 are multiplied to each of the connecting keys in an individual link while the leads from the trunks are multiplied to each of the connecting keys for an individual trunk in each link. The keys 140, 170, 260 and 190 are a part of one link and by means of them, the automatic switches, and trunks D and E, connections may be established between subscribers' substations, such as substation A and the two way trunk J. The key 190 provides a connection to the operator's telephone G so that the operator may perform the necessary services in effecting the connection.

The operator's telephone, G, may be of any well known type having the usual talking instrumentalities and a local battery feed. The operator's telephone is connected to talk key 190 over leads 31 and 32 and these leads are multiplied to identical talk keys in each link.

The auxiliary signal circuit, F, supplies battery to the lamps 181, 182, 271 and 272 and it is mul-

tiplied to all such lamps in the switchboard X. It is provided with a key by means of which the operator can connect a control relay in the battery supply circuit so that a common signal will be operated any time that any one of the associated lamps is lighted and with a cut-off key which may be operated to disconnect battery from the lamps when the switchboard X is unattended.

The calling device, H, may be of any well known type but is preferably a dial. It is connected to the dial key 160 over leads 34 and 35 which are multiplied to all of the dial keys, such as 160, in the switchboard X.

The cord circuits, such as cord K, at switchboard Y are of the universal type arranged for connection with common battery lines, such as the line N, and magneto or toll lines, such as the line P, as well as with two way trunks, such as the trunk J. The cord is also arranged for connection to an automatic switchboard. The incoming trunks from a local automatic switchboard which are not shown are answered with the plug 384 and arranged so that the cord functions the same as when the plug 381 is used with common battery line N. In extending calls to a local automatic exchange the plug 397 is used in a trunk such as the trunk R. The plug 381 is used for answering calls on two way trunks, such as trunk J, and the plug 397 is used for extending calls over such trunks.

The common equipment, N, connects to cord circuits, such as cord K, through talk keys, such as key 370, in cooperation with relays such as relay 350, through monitor keys, such as key 393, and through combined splitting and dialing relays such as relay 310. The operator's telephone, M, is similar to operator's telephone, G, and has in addition a busy test feature which provides a tip busy test from the plug 397. The calling device, S, is similar to the calling device, H, and has in addition a control lead which is grounded when the calling device is off normal to operate relays 440 and 420 and automatically connect the calling device to any cord circuit in which the key 370 and the relay 350 are operated.

The switchboard Y may be a switchboard arranged for toll and local service in a manual system and connecting with distant automatic exchanges over two way trunks such as trunk J. The switchboards at the distant automatic exchanges, such as switchboard X, provide a means for relieving the operators at the switchboard Y of such duties as recording, information and dialing when the exchange load is high and by means of switching keys such as key 265 for permitting the operators at switchboard Y to perform all these services for the automatic exchanges when the exchange load is light. The switchboard Y may be a toll and special service board associated with an automatic exchange which is arranged for connection to other automatic exchanges equipped with switchboards such as switchboard X.

The trunking and switching arrangements described above are particularly useful in systems where charges are made on all interoffice calls. They can also be used to provide full service to a connecting exchange for all of the lines in a private automatic branch exchange without services of a full time attendant at the private exchange. It will be understood, however, that the above described arrangements are by way of example only and that various modifications may be made in the circuit details by those skilled in

the art without departing from the spirit of the invention.

Having indicated the scope of my invention in general, I will now proceed to explain the operation of the particular embodiment thereof which I have shown in the drawings. For this purpose it will be assumed that both switchboards are attended and that the subscriber at substation A, Fig. 1, desires to obtain connection with the switchboard Y.

When the receiver is removed at the substation A on line 1, Fig. 1, the associated line switch extends the line to a selector in the well known manner. The subscriber then operates the calling device at the substation A causing the selector to step its wipers to the bank level associated with the incoming trunks, such as trunk D. Assuming that trunk D is the first idle incoming trunk the selector will connect the substation A to trunk D over leads 10 and 11 closing a circuit to the relay 110 from ground through its upper winding, lead 10, over the line 1, lead 11, through its lower winding to battery. The relay 110 operates armature 111 closing a circuit to relay 120 and operates armature 112 closing a circuit from ground through armature 133, lamp 182, and lead 33, to battery in the auxiliary signal circuit, F. The lamp 182 lights indicating that a call is waiting on trunk D. The relay 120 operates and connects ground to lead 12 at armature 123 to hold the calling switch train. The functions of the other armatures of the relay 120 which also operate at this time will be explained later.

The operator at the switchboard X answers by operating a connecting key and a talk key associated with one of the connecting links in the switchboard. Assuming that the operator answers on the link associated with key 140, Fig. 1, the key 140 is operated. Relay 130 is operated from ground at spring 141. The relay 130 opens the circuit to the lamp 182 at armature 133, connects ground to the lead 12 at armature 134, and closes a holding circuit to itself at armature 131 to ground through armature 122. Armature 132 operates at this time but performs no useful function. The calling line is now extended through springs 142 and 143 to link conductors 27 and 28 and to key 190. The key 190 is operated to connect the operator's telephone circuit G through springs 191 and 192 to link conductors 27 and 28 and thus to substation A.

To determine what service is desired the operator converses with the calling subscriber in the usual manner, the talking circuit may be traced from the operator's telephone over leads 31 and 32, armatures 191 and 192, armatures 142 and 143, leads 10 and 11 and the line 1 to substation A. Transmission battery is supplied to the line A through the windings of the relay 110.

To extend the substation A to the switchboard Y over one of the two way trunk circuits such as trunk J and assuming that the connection is to be made over trunk J, the key 260, Fig. 2, is operated. Ground through spring 261, armature 231, and the winding of the relay 240 to battery operates the relay 240. The relay 240 closes a locking circuit to itself through armature 241, disconnects battery from the lower winding of the relay 230 at armature 244, disconnects ground from the upper winding of the relay 230 and connects battery to the upper winding of the relay 230 at armature 243, and operates relay 250 from ground at armature 246. The relay 250 operates its armatures but has no function to perform at

this time. A circuit is now closed to the upper winding of the relay 230 in series with the relay 230, from battery at armature 243, upper winding of relay 230, contacts 222, spring 261, trunk conductor 40, armature 236, winding of relay 230 to ground. The relay 230 operates its armatures, closing a holding circuit to the relay 250 from ground through armature 233, armature 251, winding of relay 250 to battery, and closes a circuit to the lamp 271 from ground through armature 232, armature 245, spring 264, lamp 271, and lead 33 to battery. The lamp 271 lights indicating to the operator at switchboard X that the trunk line to the switchboard Y has been seized and that the operator at that switchboard has not answered. The substation A and the operator's telephone circuit are connected to conductors 27 and 28 as previously described. The operation of the key 260 extends them, through springs 262 and 263, condensers 285 and 286, contacts 222 and 224, springs 267 and 268, and trunk conductors 40 and 41, to springs 291 and 292 of jack 290.

The relay 280 operates in series with the upper winding of the relay 230 over the circuit previously traced and lights lamp 295 from ground through armature 281 and armature 287 to battery over lead 64. The lead 64 terminates in an auxiliary signal circuit such as F, Fig. 1. The lamp 295 lighted, indicates to the operator at the switchboard Y that a call is waiting on the trunk J.

The operator at the switchboard X may now restore the key 190, Fig. 1, to disconnect operator's telephone G from the trunk line and allow the calling subscriber to pass information directly to the operator at switchboard Y when she answers or the operator may leave key 190 operated and either pass information to the operator at the main exchange or supervise the passing of information by the calling subscriber.

Assuming that the operator at the switchboard Y answers with cord K, Fig. 3, the plug 381 is inserted into jack 290, Fig. 2, closing a circuit from ground through the winding of the relay 285, jack sleeve 293, sleeve of the plug 381, armature 321, armature 326 to battery through the winding of the relay 330. The resistance of the relay 285 is high enough to prevent the operation of the relay 330 at this time and as the winding of the relay 320 is short circuited by armatures 321 and 326 no operation takes place in the cord circuit K at the time the plug 381 is inserted in the jack 290. The relay 285 operates over the circuit previously traced, opens the series circuit to relays 280 and 230 at armature 286 and extinguishes the lamp 295 by opening its circuit at armature 287. The relay 280 releases and disconnects ground from armature 281. The relay 230 releases and extinguishes lamp 271 by opening its circuit at armature 232 thus indicating to the operator at switchboard X that the operator at switchboard Y has answered.

When the plug 381, Fig. 3, is inserted in jack 290, Fig. 2, the trunk conductors 40 and 41 are extended over the plug conductors to the windings 388 and 389 of the repeating coil and these windings are connected through condenser 386 thus completing a circuit from the substation A or the operator's telephone G which are connected to trunk conductors 40 and 41 over the circuit previously traced. The upper winding of the relay 325 is bridged across the condenser 386 but as there is no return path for the battery connected to trunk conductor 40 through the upper

winding of the relay 230 the relay 325 is not energized. The operator at switchboard Y then operates key 370 closing a circuit from battery through the lower winding of the relay 350, spring 373, lead 54, armature 446, Fig. 4, and armature 415 to ground and connecting lead 53 through spring 373 to armature 354. The other armatures of key 370 are also operated at this time but perform no useful function. The relay 350 operates, closes a holding circuit for itself from battery through its upper winding, armature 354, spring 373, lead 53, winding of relay 445, and armature 415 to ground, armatures 352 and 356 close a circuit for voice currents through repeating coil windings 391 and 392 and condenser 387 in series, over leads 56 and 57, and armatures 443 and 444, to the operator's telephone M. The operator at switchboard Y can now talk to the subscriber at substation A and by means of the other end of the cord terminating in plug 397 can extend the connection to any one of the lines such as the lines N, P or R terminated on the switchboard Y.

As described above the relay 445, Fig. 4, is energized in series with the upper winding of the relay 350. The relay 445 in operating disconnects lead 54 from ground at armature 446 which prevents the operation of the relay 350 in any other cord circuit in the position, and disconnects the lead 52 from the operator's telephone M at armature 447 which prevents the operator's talking circuit from being disabled if the key 393 in any cord circuit is operated.

After having completed the services requested by the subscriber at substation A the operator at switchboard Y may disconnect from the cord K by restoring the key 370 opening the circuit to the upper winding of the relay 350 at spring 373. The relay 350 releases and disconnects the operator's telephone, M, from the cord K at armatures 352, 353, 355 and 356. The relay 445 also restores at this time and connects ground to the lead 54, so that the common equipment L is in condition to operate with any of the cord circuits in the position.

When the calling subscriber replaces the receiver at the substation A the relay 110, Fig. 1, releases, opens the circuit to the relay 120 and short circuits the relay 130 at armature 111, and closes a circuit to the lamp 181 from ground at armature 112, through armature 132 and spring 144 to battery over lead 33. The lamp 181 lights indicating to the operator at switchboard X that the connection should be released. The relay 130 releases, opens its holding circuit at armature 131, opens the circuit to lamp 181 at armature 132. The relay 120 is slow to release but shortly after its circuit is opened at armature 111 the relay 120 releases, removes the short circuit from the winding of the relay 130 at armature 121 and disconnects ground from lead 12 at armature 123, allowing the calling switch train to release.

The relay 130 operates when the short circuit is removed from its winding, opens the circuit to lamp 182 at armature 133, grounds lead 12 at armature 134 to make the trunk D busy to subsequent calls, and closes a circuit to the lamp 181 at armature 132.

To release the connection the operator at switchboard X restores the key 140 and the key 260. When key 140 is restored the circuit to the relay 130 is opened at spring 141 and lamp 181 is extinguished as its circuit is opened at spring 144. The relay 130 restores and removes ground from the lead 12 at armature 134 making the trunk D available to subsequent calls. When the

key 260 is restored the circuit to relay 240 is opened at spring 261. The relay 240 releases, disconnects battery from the upper winding of the relay 230, connects ground to the upper winding of the relay 230, connects battery to the lower winding of the relay 230, and opens the circuit to the relay 250 which is slow acting and remains operated for a short time after its circuit is opened. A circuit can now be traced from battery through resistor 274, armature 244, lower winding of relay 230, contact 224, spring 268, lead 41, spring 292, center conductor of plug 381, winding 389, armature 332, upper winding of relay 325, armature 331, winding 388, upper conductor of plug 381, spring 291, lead 40, spring 267, contact 222, upper winding of relay 230, and armature 233 to ground. The relay 230 operates, closes a circuit to the relay 250, which because of its slow acting feature has remained operated, from ground through armatures 233 and 251 and the winding of relay 250 to battery, and closes a circuit to the lamp 273 from ground through armature 232, armature 245, armature 252, armature 226 and the lamp 273 to battery. The lamp 273 lights and is an indication to the operator at switchboard X that the trunk has not been released at switchboard Y. The relay 325 operates in series with the relay 230 over the circuit previously traced and opens the short circuit to the winding of the relay 320 at armature 326 thus energizing the relay 320 in series with the relays 330 and 285 over the circuit previously traced. The relay 320 operates and closes a circuit from ground through the armature 322, armature 333, and lamp 382 to battery. The lamp 382 lights, indicating to the operator at switchboard Y that the trunk J has been disconnected at switchboard X.

To disconnect, the operator at switchboard Y removes the plug 381 from the jack 290 opening the circuits to the relays 320, 325, 285, and 230. The relay 320 releases and opens the circuit to the lamp 382 at armature 332 which is extinguished. The relay 325 releases and short circuits the winding of relay 320 at armature 326. The relay 285 releases, connects the lamp 295 through armature 287 to armature 281, and connects the winding of the relay 280 through armature 286 to the lead 40. The relay 230 releases and at armature 232 opens the circuit to the lamp 273 which is extinguished, and at armature 233 opens the circuit to the relay 250, which shortly thereafter releases. The trunk J is now available to calls originating at either switchboard.

Assuming now that both switchboards are attended and that the operator at switchboard Y has answered one of the lines or trunks terminating on the switchboard with plug 381, has connected the operator's telephone M to the cord circuit K by means of the key 370 and the relay 350 as previously described, and finds that the calling subscriber desires a connection with a subscriber in the automatic exchange. The plug 397 is inserted in the jack 290 completing a circuit from battery through the winding of the relay 340, armature 346, armature 362, lower conductor of plug 397, spring 293, and the winding 70 of the relay 285 to ground. The resistance of the relay 285 is high enough to prevent the operation of the relay 340 but the relay 285 operates, disconnects the relay 280 from the lead 40 at armature 286, and disconnects the lamp 295 from the armature 281 at armature 281. A circuit is

11

also completed to the relay 345 in series with the relay 230 which may be traced from ground through armature 243, upper winding of relay 230, contact 222, spring 267, lead 40, spring 291, upper conductor of plug 397, armature 353, lead 58, back contacts associated with spring 451, armature 434, lead 56, armature 352, repeating coil winding 391, armature 341, windings of relay 345, armature 336, armature 361, armature 342, repeating coil winding 392, armature 356, lead 57, armature 435, back contacts associated with spring 452, lead 59, armature 355, center conductor of plug 397, spring 292, lead 41, spring 268, contacts 224, lower winding of relay 230, armature 244 and resistor 274 to battery. The relay 345 is a polarized relay which operates when negative battery is connected to its right terminal and positive battery is connected to its left terminal, and which releases on open circuit or when positive battery is connected to its right terminal and negative battery is connected to its left terminal. As negative battery is connected to the right terminal and positive battery to the left terminal over the circuit previously traced, the relay 345 operates, closes a circuit from battery through lamp 398, armature 343 and armature 347 to ground causing the lamp 398 to light, and at armature 346 opens a short circuit to the winding of the relay 360. As the key 370 is operated the winding of the relay 360 is short circuited at spring 375 so the relay 360 cannot operate at this time.

The relay 230 operates in series with the relay 345 over the circuit previously traced, closes a circuit from ground through armature 232, armature 245, armature 252, lamp 272, and lead 33 to battery in auxiliary signal circuit F causing the lamp 272 to light and signal the operator at switchboard X, transfers armature 231 from the winding of the relay 240 to the winding of the relay 220, and connects ground through armature 233 to armature 251. The operator at switchboard X answers by operating a connecting key and a talk key associated with one of the connecting links in the switchboard. Assuming that the operator answers on the link associated with key 260, the key 260 is operated and a circuit is closed from ground through spring 261, armature 231, armature 242 and the winding of the relay 220 to battery, the trunk conductors 40 and 41 are extended to key 190 through the condensers 275 and 276, and the springs 262 and 263, and a circuit is prepared for the lamp 271 through spring 264. The relay 220 operates its armatures, reversing the direction of current flow over the trunk conductors 40 and 41 by means of armatures 221 and 223 and their associated contacts the effect of which will be described later, disabling the lamp 273 at armature 226, and operating the relay 250 from ground through armature 225. The relay 250 operates, extinguishes the lamp 272 by opening its circuit at armature 252, and closes a holding circuit to itself through armatures 251 and 233. The reversal of current over the trunk conductors 40 and 41, energizes the relay 345 from negative battery on its left terminal to positive battery on its right terminal. The relay 345 restores, and disconnects ground from armature 347 thus extinguishing the lamp 398, indicating to the operator at switchboard Y that the operator at switchboard X has answered.

The operator at switchboard X then operates key 190 connecting operator's telephone G over 31 and 32, leads 27 and 28, springs 262 and 263 and condensers 275 and 276 to trunk conduct-

12

tors 40 and 41 and to the cord circuit K at switchboard Y. Assuming that the operator at switchboard Y has not disconnected, by restoring the key 370, a talking circuit is completed between operators' telephones G and M. The operator at switchboard X determines what service is required by switchboard Y and can extend the connection to a subscriber's substation such as substation A in the automatic office over an outgoing trunk such as trunk E. Assuming that the trunk E is used for this purpose the key 160 is operated closing the circuit to the line switch LS over lead 13, contacts associated with spring 161, left winding of relay 150, spring 175, contacts associated with spring 162, and lead 14. The line switch LS extends outgoing trunk E to a selector such as SEL in the well known manner and the operator at switchboard X may then extend the connection by means of the calling device which is connected to the trunk by the operation of the key 160. The operation of the key 160 disconnects the operator's telephone G and the trunk J from the automatic switch train at the contacts associated with springs 161 and 162.

After operating the calling device to cause a selector and a connector to extend the connection to the substation A, the operator at switchboard X restores the key 160 disconnecting the calling device from outgoing trunk E and reconnecting the left winding of the relay 150 to the leads 13 and 14 by means of springs 161 and 162 and the contacts associated with them. The operation of the key 170 which connected the left winding of the relay 150 to leads 13 and 14 also connected leads 13 and 14 through springs 173 and 174 and springs 262 and 263 to leads 40 and 41, closed the circuit from battery through the right winding of relay 150 to ground at spring 171, and connected the lamp 181 through spring 172 to a contact on the relay 150. The relay 150 is a polarized relay and its windings are aiding at this time so that it will operate and light the lamp 181 from ground at armature 151 through spring 172 to battery over lead 33.

The operator at switchboard X now restores the key 190 disconnecting operator's telephone G from the trunk at springs 191 and 192. When the receiver is removed at the substation A the connector reverses the direction of current flowing over the leads 13 and 14 causing the relay 150 to release and extinguish the lamp 181 by opening its circuit at armature 151 to indicate to the operator at switchboard X that the call has been answered.

The operator at switchboard Y will usually disconnect immediately after the operator at switchboard X has been given the information necessary to complete the connection by restoring the key 370, thus allowing the relays 350 and 445 to restore as previously described.

A talking circuit may now be traced from the substation A, through connector CONN, selector SEL, and line switch LS over leads 13 and 14, contacts associated with springs 161 and 162, springs 173 and 174, leads 27 and 28, springs 262 and 263, condensers 275 and 276, contacts 222 and 224, springs 267 and 268, trunk conductors 40 and 41, springs 291 and 292, upper and center conductors of plug 397, contacts 357 and 358, repeating coil windings 391 and 392, and the condenser 387. Voice currents developed in this circuit induce similar currents in the windings 388 and 389 of the repeating coil which are connected in series through condenser 386 and these induced currents are transmitted over the upper and center

conductors of the plug 381 to the line conductors N^1 and N^2 of a line circuit, such as circuit N, with which the plug 381 has been connected and over the conductors N^1 and N^2 to the substation or other equipment connected thereto. Likewise voice currents developed in the repeating coil windings 388 and 389 by the talking instrumentalities associated with the line to which the plug 381 has been connected induce similar currents in the windings 391 and 392 which are transmitted to the substation A over the circuit previously traced.

When the receiver is replaced at the substation A the connector CONN changes the direction of the current flowing over leads 13 and 14 causing relay 150 to operate and close the circuit to the lamp 181 from ground at armature 151. The lamp 181 lights, indicating to the operator at switchboard X that the substation A has been disconnected. The operator at switchboard X then restores the key 170, extinguishing the lamp 181 by opening its circuit at spring 172, disconnects the bridge of the left winding of the relay 150 from the leads 13 and 14 to allow the automatic switches to release, opens the circuit to the right winding of the relay 150 at spring 171 and disconnects from the leads 27 and 28 at springs 173 and 174. The relay 150 releases when the circuit to its windings are opened at the springs of the key 170 but performs no function. The operator at the switchboard X then restores the key 260 opening the circuit to the relay 220 at spring 261 and disconnecting the leads 27 and 28 from the trunk J at springs 262 and 263. The relay 220 releases, reverses the direction of the current flowing over trunk conductors 40 and 41 at armatures 221 and 223, disconnects ground from the winding of the relay 250 at armature 225, and closes the circuit from battery through lamp 273, armature 226, armature 252, armature 245 and armature 232 to ground. The lamp 273 lights indicating to the operator at switchboard X that the trunk J has not been released at the switchboard X. The windings of the polarized relay 345 in cord K are now energized in the direction for operating the relay by the current flowing over trunk conductors 40 and 41. The relay 345 operating closes a circuit from ground through armature 347, armature 343, and lamp 398 to battery, and opens the short circuit around the winding of the relay 360 at armature 346. The lamp 398 lights indicating to the operator at switchboard Y that the trunk J has been disconnected at switchboard X. The relay 360 is now energized over a circuit which may be traced from battery through the winding of the relay 340, the winding of the relay 360, lower conductor of plug 397, spring 295 through the winding of relay 285 to ground. The relay 360 operates, opens a part of the incomplete short circuit for its winding at armature 362, connects the lamp 398 through armature 363 to ground through armature 337, and opens the short circuit around the lower winding of the relay 335 at armature 361. The lower winding of the relay 335 is now energized in series with the relay 345 and the relay 230 over the circuit previously traced. The relay 335 operates, opens a part of the incomplete short circuit to its lower winding at armature 336, and disconnects ground from armature 337, thus placing the circuit for the lamp 398 entirely under control of the relay 345.

The operator at the switchboard Y disconnects from the trunk J by removing the plug 397 from the jack 290 opening the circuits to the relays 345, 335 and 230 at springs 294 and 292, and opening the circuit to the relays 360 and 285 at spring

293. The relays 335, 345, and 360 release, the lamp 398 being extinguished when its circuit is opened at armature 347. The operator at switchboard Y also disconnects the plug 381 from the line with which it had been connected allowing the apparatus in the end of the cord associated with the plug 381 to restore so that cord circuit K will be conditioned for use in completing other connections. The relay 285 releases connecting the relay 280 to trunk conductor 40 at armature 236, and connecting the lamp 295 through armature 287 to armature 281. The relay 230 releases, transferring the armature 231 from the winding of the relay 220 to the winding of the relay 240, opening the circuit to the relay 250 at armature 233, and extinguishing the lamp 273 by opening its circuit at armature 232. The relay 250 releases shortly after its circuit is opened at armature 233, disconnects armature 251 from its left terminal, and connects armature 252 to the lamp 272. Lamp 273 being extinguished indicates to the operator at switchboard X that the trunk J has been disconnected at switchboard Y. The trunk J is now at normal and available for use on other connections.

Assuming now that the switchboard X is unattended and that the operator before leaving the switchboard operated the switching keys, such as key 265, in the two way trunks, such as two way trunk J, and that the subscriber at the substation A wishes to extend a call to the switchboard Y. When the receiver at the substation A is removed the substation A is connected by means of the line I and its individual line switch over a trunk line such as line 4 to a selector such as selector SEL. Assuming that the selector SEL has been seized it will step its wipers to the level associated with incoming trunks such as trunk D in response to the operation of the calling device at the substation A and will automatically search for an idle trunk. Assuming that the trunk D is the first idle trunk, the relay 110 will be energized in series with the calling substation as previously described. The relay 110 energizes the relay 120 from ground at armature 121, and connects ground through armature 112 and armature 133 to the lamp 182. A battery cut-off key, not shown, is provided in the auxiliary signal circuit F for the disconnection of battery from the lamps, such as lamp 182, when the switchboard X is unattended. However, the lamp 182 has no function to perform in the trunk circuit D when the switching key 265 is operated. The relay 120 operates its armatures, armatures 121 and 122 having no function to perform. Armature 123 connects ground over lead 12 to selector SEL to hold the automatic switches and connects ground through spring 266 over lead 15 to the B. C. O. relay of the line switch LS to clear the leads 13 and 14, which have been connected through springs 267 and 268 to trunk conductors 40 and 41 of attachments and thus prevent any interference with this connection by the line switch LS. The ground on lead 12 also makes the trunk D inaccessible to other selectors. The relay 210 is energized from ground at armature 124 through spring 269 and operates its armatures. Lead 10 is connected through armature 211 to condenser 275, lead 11 is connected through armature 215 to condenser 276, trunk conductor 40 is connected through armature 213 and contacts 222 to the upper winding of relay 230, trunk conductor 41 is connected through armature 214 and contacts 224 to the lower winding of the relay 230, and the relay 240

is energized from ground through armature 212. The relay 240 operates its armatures, the armatures 241 and 245 having no function to perform. Armature 242 opens part of the incomplete circuit to relay 220, armature 243 disconnects ground from the upper winding of the relay 230 and connects said winding to battery through resistance 274, armature 244 disconnects battery through resistance 274 from the lower winding of the relay 230, and the relay 250 is energized from ground at armature 246. The relay 250 operates its armatures, armature 251 connecting the winding of the relay 250 to armature 233 and armature 252 being connected through armature 226 to the lamp 273.

A circuit may now be traced from battery through resistance 274, armature 243, upper winding of relay 230, contacts 222, armature 213, trunk conductor 40, armature 286 and the winding of relay 280 to ground. The upper winding of the relay 230 and the relay 280 are thus energized in series. The relay 230 operates its armatures, which perform no useful function at this time. The relay 280 operates and closes a circuit from battery over lead 64 through lamp 295 and armature 287 to ground through armature 281, thus lighting the lamp 285 to signal the operator at switchboard Y.

The operator at the switchboard Y answers by inserting a plug, such as plug 381, of a cord circuit, such as cord K, into jack 290. Assuming that cord K is used in this case, the relay 285 is energized over spring 293, lower conductor of plug 381 and the winding of the relay 330 as previously described. The relay 285 operates its armatures, armature 286 opening the series circuit to the relays 280 and 230, and armature 287 extinguishing the lamp 295 by opening its circuit. The relay 280 restores and disconnects armature 281 from ground. The relay 230 restores its armatures which have no effect on the performance of the circuits at this time. The insertion of the plug 381 into jack 290 connects the upper conductor of plug 381 to spring 291 and the center conductor of plug 381 is connected to spring 292. A talking circuit can now be traced from substation A over line 1, through the line switch individual to line 1, over trunk line 4, through selector SEL, leads 10 and 11, armatures 211 and 215, condensers 275 and 276, contacts 222 and 224, armatures 213 and 214, trunk conductors 40 and 41, springs 291 and 292, upper and center conductors of plug 381 and repeating coil windings 388 and 389 in series with condenser 386. The upper winding of the relay 325 is also connected in series with the repeating coil windings 388 and 389 but does not operate at this time as there is no power source connected to the circuit. The operator at switchboard Y connects operator's telephone M to repeating coil windings 391 and 392 in series with condenser 387 by means of talk key 370 and relay 350 as previously described. Voice currents generated at substation A flow through repeating coil windings 388 and 389 and induce similar currents in repeating coil windings 391 and 392 which are transmitted to operator's telephone M over leads 56 and 57, while voice currents generated at operator's telephone M flow through repeating coil windings 391 and 392 and induce similar currents in repeating coil windings 388 and 389 which are transmitted to the substation A over the circuit previously traced. The operator at switchboard Y may now extend the connection and disconnect from the cord circuit as previously described.

When the receiver is replaced at substation A the circuit to the relay 110 is opened. The 110 restores its armatures, the circuit to the relay 120 being opened at armature 111, and armature 112 having no function to perform at this time. The relay 120 restores its armatures, armatures 121 and 122 having no function to perform. Armature 123 disconnects ground from the lead 12 to release the automatic switches and from the lead 15 to release the B. C. O. relay of the line switch LS. The circuit to relay 210 is opened at armature 124 permitting the relay 210 to restore its armatures. Leads 10 and 11 are disconnected at armatures 211 and 215 from condensers 275 and 276 respectively. Armature 213 disconnects condenser 275 and the upper winding of the relay 230 from trunk conductor 40. Armature 214 disconnects condenser 276 and the lower winding of the relay 230 from trunk conductor 41. The circuit to the relay 240 is opened at armature 212. The relay 240 restores its armatures, armatures 241 and 245 having no function to perform at this time. Armature 242 is connected to the winding of relay 220, armature 243 disconnects battery from the upper winding of relay 230 and connects said winding to ground, armature 244 connects the lower winding of relay 230 to battery through resistance 274, and armature 246 opens the circuit to the relay 250. Shortly after its circuit is opened the relay 250 restores, disconnects armature 251 from its winding and connects armature 252 to the lamp 272.

As previously mentioned the circuit to the B. C. O. relay of the line switch LS is opened at armature 123 when relay 120 releases. The B. C. O. relay releases and the line relay of the line switch operates in series with the upper winding of the relay 325 from a circuit which may be traced over leads 13 and 14, springs 267 and 268, trunk conductors 40 and 41, springs 291 and 292, upper and center conductors of plug 381, repeating coil windings 388 and 389, armatures 331 and 332 and the upper winding of relay 325. The line switch operates and seizes a selector, such as SEL, in the well known manner causing ground to be returned over lead 15, through spring 266 to lead 12 to make the trunk D inaccessible to other selectors. The relay 325 operates its armatures, armature 326 opening the short circuit around the winding of the relay 320 and armature 327 disconnecting ground from part of an incomplete circuit for lamp 382. The relay 320 is energized from battery through the winding of relay 330, winding of the relay 320, lower conductor of plug 381, and spring 293, through the winding of relay 285 to ground. The relay 320 operates, armature 321 opening a part of the incomplete short circuit to the winding of the relay 320, and armature 322 closing a circuit from ground, through armature 333, and lamp 382 to battery over lead 64 which is connected to an auxiliary signal circuit similar to auxiliary signal circuit F of Fig. 1. The lamp 382 lights indicating to the operator at switchboard Y that the trunk J has been disconnected at the automatic office.

The operator at the switchboard Y disconnects from the trunk J by removing the plug 381 from the jack 290, opening the circuit to the relays 320 and 285 at spring 293, and opening the circuit to the relay 325 at springs 291 and 292. The relay 320 restores, closes a part of the incomplete short circuit to its winding at armature 321, and extinguishes the lamp 382 by opening

its circuit at armature 322. The relay 325 restores, short circuiting the winding of the relay 320 at armature 326, and preparing a circuit to the lamp 382 at armature 327. The relay 285 restores, connecting the relay 280 to trunk conductor 40 at armature 286, and connecting armature 287 to the lamp 295.

The holding bridge for the selector which had been seized by the line switch LS is also opened at springs 291 and 292 when the plug 384 is removed from the jack 290. The selector and the line switch LS release and ground which has been extended over lead 15 through spring 266 to lead 12 is disconnected. Trunk D is now accessible to the selectors and the trunk J has restored to normal and may be seized at either end for establishing other connections.

Assuming now that the operator at switchboard Y has answered a call on one of the lines such as the line N with the cord circuit K, that the plug 384 has been connected with the line N, that the operator's telephone M has been connected to repeating coil windings 391 and 392 as previously described and that the connection is to be extended to the substation A in the automatic office over the two way trunk J. The operator at switchboard Y inserts the plug 397 into jack 290 closing a circuit from battery through the winding of relay 340, armature 346, armature 362, lower conductor of plug 397, and spring 293 to ground through the winding of relay 285. The resistance of the winding of the relay 285 is high enough to prevent the operation of the relay 340, however the relay 285 operates its armatures disconnecting the relay 280 from trunk conductor 40 at armature 286, and disconnecting armature 287 from the lamp 295. A circuit is also closed now to the winding of the polarized relay 345 which may be traced through armatures 341 and 342, repeating coil windings 391 and 392, armatures 352 and 356, leads 56 and 57, armatures 434 and 435, contacts 453 and 454, leads 58 and 59, armatures 353 and 355, upper and center conductors of plug 397, springs 291 and 292, springs 267 and 268 over leads 13 and 14 to ground and battery at the line switch LS. The direction of current flowing in this circuit is such that the relay 345 operates its armatures, closing a circuit from ground through armature 347, armature 343 and lamp 398 to battery, and opening part of a short circuit around the winding of the relay 360 at armature 346. The lamp 398 lights indicating to the operator at switchboard Y that the line switch LS has been seized. As the talk key 370 is operated the winding of the relay 360 is short circuited by spring 375 and the relay 360 cannot operate at this time.

The line switch LS operates in series with the windings of the relay 345 extending the connection over a trunk line such as line 4 to a selector such as selector SEL. Assuming that in this case the connection is extended over trunk line 4 to selector SEL the line relay of the selector SEL is operated in series with the windings of the relay 345, ground is returned over the trunk line 4 to the line switch LS to hold it operated and from the line switch over lead 15, and spring 266 to lead 12 to make trunk D and therefore trunk J inaccessible to the selectors, and dial tone will be forwarded to operator's telephone M over the circuit previously traced. The operator at switchboard Y will normally have been advised that the switchboard X is unattended and upon hearing dial tone will operate the calling

device S to send out the code required to step the selector SEL to a connector such as connector CONN, which will be assumed to be the connector used in this case, and to step the connector CONN to the line 1 to which substation A is connected.

When the calling device S is off-normal, ground from the calling device through the winding of the relay 440 to battery energizes the relay 440 which operates and as its armature is attracted the pair of springs represented by the armature 442 are closed first connecting the condenser 475 to the leads 58 and 57 to minimize the noise caused by transferring from the holding bridge through the windings of the relay 345 to the impulsing bridge in the calling device S. The relay 440 continues to operate in full and thus all of the springs of the relay are actuated. Armatures 443 and 444 disconnect the operator's telephone M from the leads 58 and 57 respectively. Armature 441 extends ground from the calling device to the winding of the relay 430 which operates and as its armature is attracted the pairs of springs represented by armatures 432 and 433 are closed first. One side of the impulsing bridge in the calling device S is connected through spring 467, resistance 474, armature 432, contacts 454, lead 59, and armature 353 to the center conductor of plug 397 and the other side of the impulsing bridge is connected through armature 433, contacts 453, lead 58, and armature 353 to the upper conductor of plug 397. The line relay of the automatic switch connected to trunks' conductors 40 and 41 and through jack springs 291 and 292 to the upper and center conductors of plug 397 is momentarily held by the bridge of the windings of the polarized relay 345 in multiple with the resistance 474 and the impulsing bridge in calling device S in series. The relay 430 continues to operate in full and thus all of the springs of the relay are actuated. The bridge of the windings of polarized relay 345 is disconnected from the impulsing bridge and from the plug 397 at armatures 434 and 435 and the resistance 474 is short circuited at armature 431. The line relay of the automatic switch connected to the cord K is thus under control of the impulsing bridge and will cause the switch to step in the well known manner in response to impulses generated in the bridge by the calling device S. After each digit the ground may be disconnected at the calling device and reconnected shortly before the next digit is to be transmitted. If the interval between digits is long enough relays 430 and 440 may release and transfer the circuit for the line relay of the automatic switch connected to the cord K to the windings of polarized relay 345. However, after the last digit has been transmitted and the calling device S has restored to normal the circuits to relays 430 and 440 will be opened for a long enough interval to allow them to release. The sleeve on the relay 440 makes it relatively slow to release so the relay 430 restores its armatures first. Armature 431 first removes the short circuit from the resistance 474, armatures 434 and 435 then connect the repeating coil windings 391 and 392 and the windings of the polarized relay 345 to the automatic switch connected to cord K, and finally armatures 432 and 433 disconnect the impulsing bridge from the cord circuit K. The relay 440 in restoring first disconnects the winding of the relay 430 from the calling device at armature 441, then connects the operator's telephone M to cord K at armatures 443 and 444 and finally disconnects the

condenser 415 from the cord K at armature 442. The sequence of the operation of the armatures of relays 430 and 440 minimizes the noise transmitted to the line N while transferring to and from the impulsing bridge.

After the operator at switchboard Y has dialled the digits required to reach substation A the talk key 370 may be left operated until the either ring back tone or busy tone is returned by connector CONN. Assuming that the line I is free, the operator after hearing the ring back tone may disconnect the operator's telephone M from the cord by restoring the talk key 370 thus allowing relays 350 and 445 to release as previously described. The short circuit to the winding of the relay 360 is opened at spring 375 when the talk key 370 is restored. A circuit can now be traced from battery through the winding of relay 340, through the winding of the relay 360, the lower conductor of plug 397 and spring 293 through the winding of relay 285 to ground. The relay 360 operates, armature 361 opening a short circuit around the lower winding of the relay 335, armature 362 opening part of an incomplete short circuit around the winding of the relay 360, and armature 363 connecting a multiple ground to the lamp 398 through armature 337. The lower winding of the relay 335 is now energized in series with the windings of polarized relay 345 and operates its armatures, opening part of the incomplete short circuit around its own winding at armature 336, and disconnecting ground from the armature 363 and thus from lamp 398 at armature 337 so that the circuit to the lamp 398 remains under control of the polarized relay 345.

When the receiver at the substation A is removed the connector reverses the direction of current to the polarized relay 345 over the circuit previously traced causing the relay 345 to restore its armatures. Armature 346 closes part of an incomplete short circuit around the winding of relay 360, and armature 347 opens the circuit to the lamp 398. The lamp 398 is extinguished indicating to the operator at switchboard Y that the subscriber at substation A has answered.

When the subscriber at substation A disconnects, the direction of the current for energizing the coils of polarized relay 345 is again changed causing the relay 345 to operate its armatures. Ground through armature 347, armature 343 and the lamp 398 to battery causes the lamp 398 to light indicating to the operator at switchboard Y that the subscriber at substation A has disconnected.

The operator at switchboard Y disconnects from the trunk J by removing the plug 397 from the jack 290 opening the circuit to relays 335 and 345 at the upper and center conductors of plug 397 and opening the circuit to relay 360 at the lower conductor of plug 397. The plug 381 is also disconnected from the line N and the apparatus of cord K restores to normal making the cord ready for use on other connections.

The holding circuit to the automatic switches is opened at springs 291 and 292 when plug 397 is removed from jack 290. The automatic switches release and ground over lead 15 and spring 266 to lead 12 is disconnected making trunk D accessible to the selectors. The circuit to the relay 285 is opened at spring 293 when plug 397 is removed from jack 290 allowing the armatures of the relay to restore. Armature 286 connects relay 280 to trunk conductor 40 and armature 287 is connected to lamp 295. The two way trunk J is available for

establishing other connections between the automatic office and the switchboard Y.

It may be noted in trunk J that with the key 265 operated the lamp 295 at switchboard Y will not light in response to the operation of the key 260. The operation of the key 260 operates the relay 240, as previously described, which in turn operates the relay 250 and connects battery through resistance 274 to the upper winding of the relay 230. The series circuit to the upper winding of the relay 230 and the winding of the relay 280 is open at spring 267 and therefore the relays 230 and 280 do not operate. However, should the trunk D be seized by one of the subscribers' lines the relays 110 and 120 operate and the relay 210 is operated from ground at armature 124. The series circuit to the upper winding of the relay 230 and the winding of the relay 280 is closed through armature 213. The lamp 271 will be lighted by the operation of the relay 230 and the lamp 295 will be lighted by the operation of the relay 280. Both lamps will be extinguished when the relays 230 and 280 release after their circuit is opened by the operation of relay 285 in response to the answering of the call at switchboard Y. The release of the connection and the guarding of the trunk against intrusion until both ends have been disconnected are entirely under control of the subscriber line through trunk D and the switchboard Y. When a call is originated at switchboard Y on the trunk J the relay 210 is not operated and hence the key 260 can have no effect of performance of the trunk J or the associated apparatus.

When an operator is again assigned to the switchboard X the switching keys, such as key 265, in the two way trunks, such as trunk J, are restored and battery is connected to the lamps, such as 181, 182, 271 and 272 through auxiliary signal circuit F. Connections between the switchboard Y and the automatic office will then be routed through the connecting links on the switchboard X as previously described.

Having described my invention, what is considered to be new and is desired to be protected by Letters Patent will be set forth in the following claims.

What is claimed is:

- 50 1. In a telephone system, an automatic exchange, said exchange including a plurality of connecting links and a plurality of incoming trunks and a plurality of outgoing trunks, an automatic switch individual to each outgoing trunk, a second exchange, a plurality of two way trunks connecting said exchanges, means including any one of said links for establishing connections from said automatic exchange to said second exchange over any one of said two way trunks through any one of said incoming trunks, means including any one of said links for establishing connections from said second exchange to lines in said automatic exchange over any one of said two way trunks through any one of said outgoing trunks including the automatic switch individual thereto, and switching means individual to said two way trunks for enabling connections to be established from said automatic exchange to said second exchange over an individual one of said incoming trunks and an individual one of said two way trunks independent of said links, and for enabling connections to be established from said second exchange to said automatic exchange through the automatic switch of an individual one of said outgoing

trunks and said individual two way trunk independent of said links.

2. In a telephone system, an operator attended switchboard in one exchange and an operator attended switchboard in an automatic exchange, incoming trunks and outgoing trunks in said last switchboard, a two way trunk line connecting said switchboards, means for establishing inter-exchange connections over said trunk line and any one of said incoming trunks or any one of said outgoing trunks with the assistance of operators at said switchboards, and means in said automatic exchange for operatively associating said trunk line with one of said incoming trunks and with one of said outgoing trunks so that interexchange connections may be established thereover with the assistance of an operator at said first switchboard.

3. In a telephone system, an automatic exchange including subscribers' lines, an operator attended switchboard, automatic switches for enabling connections to be established between said subscribers' lines and said switchboard, a second exchange, a trunk line connecting said exchanges, operator controlled means in said switchboard for extending said connections to said second exchange over said trunk line, and switching means in said switchboard for operatively associating said trunk line with said automatic switches so that connections may be established between said subscribers' lines and said second exchange independent of said operator.

4. In a telephone system, an automatic exchange having subscribers' lines and automatic switches, an operator attended switchboard thereat, a two way trunk line, a second exchange, means including more than one of said automatic switches for enabling said operator to establish connections over said trunk line between said second exchange and said subscriber lines, and switching means in said switchboard for connecting said trunk line with one of said automatic switches to enable connections to be established between said second exchange and said subscribers' lines independent of said operator.

5. In a telephone system, automatic switches, a first switchboard, a second switchboard, a two conductor trunk connecting said switchboards, a signal for said trunk in each switchboard, a key in said trunk, means for operating either the signal at the first switchboard or one of said automatic switches in response to the closure of said trunk conductors at the second switchboard depending on whether said key is normal or operated, means including only one of said trunk conductors for operating the signal at the second switchboard, said last means operative either under control of said first switchboard or under control of any one of a plurality of said automatic switches depending on whether said key is normal or operated.

6. In a telephone system, an automatic exchange, subscribers' lines, a first switchboard, incoming trunk circuits in said switchboard accessible to said subscribers' lines, a second switchboard, a two way two conductor trunk connecting said switchboards, a signal for said trunk at each switchboard, a key, connecting means in said first switchboard for connecting any one of said incoming trunks to said two way trunk, control means including only one conductor of said trunk for operating the signal at said second switchboard, said control means responsive either to the operation of said connecting means or to the seizure of an individual one of said incoming

trunks by one of said subscribers' lines depending on whether said key is normal or operated, outgoing trunks from said first switchboard to said automatic exchange, a line switch for each outgoing trunk, either means for operating the signal at said first switchboard or the line switch of an individual one of said outgoing trunks operative in response to the closure of the two conductors of said trunk at said second switchboard depending on whether said key is normal or operated, and means including part of said connecting means for connecting said two way trunk to any one of said outgoing trunks, the line switch of said one outgoing trunk being operative in response to said last means.

7. In a telephone system, two switchboards, a two conductor trunk connecting said switchboards, a line relay and a line signal at each switchboard, the line relay at one of said switchboards operative in response to the closure of said trunk conductors at the other of said switchboards to operate the line signal at said one switchboard, a key at said one switchboard, a control relay at said one switchboard operative in response to the operation of said key, the line relay at said other switchboard being operative over one of said trunk conductors in response to the operation of said control relay to operate the line signal at said other switchboard.

8. In a telephone system, an attendant's switchboard comprising a line relay, a line signal, a supervisory signal, a connecting key and a control relay; a manual switchboard comprising a line relay, a line signal and a cut-off relay; a two conductor trunk connecting said switchboards; the line relay at said attendant's switchboard operative in response to the closure of said trunk conductors in case said trunk is taken for use at said manual switchboard; the line signal at said attendant's switchboard being operative in response to the operation of said line relay; said control relay operative in response to the operation of said connecting key when said trunk is taken for use at said attendant's switchboard to operate the line relays at each of said switchboards over only one of said trunk conductors; in case said control relay is operated the line signal at said manual switchboard being operative in response to the operation of the line relay thereat and said supervisory signal being operative in response to the operation of the line relay at said attendant's switchboard; said cut-off relay being operated in response to answering at said manual switchboard to release said line relays to operate said last mentioned line signal, said supervisory signal being operated in response to the release of the line relay at said attendant's switchboard, thereafter said last mentioned line relay being inoperative in response to the closure of said trunk conductors.

9. In a telephone system, two switchboards, a two conductor trunk connecting said switchboards, a double wound relay and a battery at one of said switchboards, one side of one winding of said double wound relay connected to one of said conductors and the other side of said one winding connected to ground, one side of the other winding of said double wound relay connected to the other of said conductors and the other side of said other winding connected to the negative pole of said battery, the positive pole of said battery being connected to ground, said relay operative in response to the closure of said trunk conductors at the other of said switchboards, a line signal at said one switchboard operative in response to the operation of said double

wound relay, a single wound relay at said other switchboard; one side of said winding being connected to ground and the other side of said winding being connected to said one trunk conductor, a control relay at said one switchboard, a key for operating said control relay, said one winding of said double wound relay being disconnected from ground and connected to the negative pole of said battery for energizing said double wound relay and said single wound relay over said one trunk conductor in response to the operation of said control relay, another line signal at said other switchboard being operative in response to the operation of said single wound relay and a supervisory lamp at said one switchboard being operative in response to the operation of said double wound relay in case said key is operated.

10. In a telephone system, two switchboards, a two conductor trunk connecting said switchboards, signals for said trunk, a cord circuit having signal control devices at one switchboard, means responsive to the initiation of a call at said one switchboard and including one of said signal control devices and a relay for establishing a current flow over the two conductors of said trunk to operate a signal thereof at the other switchboard, means responsive to the answering of said signal for reversing the direction of current flow over said trunk conductors to operate said one signal control device, control means responsive to the initiation of a call at said other switchboard for establishing a current flow over one conductor of said trunk, means responsive to said last current flow for operating another signal thereof at said one switchboard, means responsive to the answering of said other signal for preventing current flow over said trunk conductors, said control means responsive to disconnecting at said other switchboard for establishing another current flow over said trunk conductors, another of said signal control devices at said one switchboard operative in response to said other current flow and said relay operative in response to said other current flow to operate a further one of said signals at said other switchboard to indicate that said trunk has not been disconnected at said one switchboard.

11. In a telephone system, an automatic exchange including subscribers' lines, a control circuit accessible to said lines, two switchboards, a trunk including a switching key connecting said switchboards, a connecting key for said trunk at one of said switchboards, a signal for said trunk at each switchboard, relays for operating said signals responsive to the operation of said connecting key with said switching key normal, means responsive to the seizure of said control circuit by one of said lines for operating said relays one of which operates the signal at the other of said switchboards with said switching key operated, said last means effective for operating the signal at each of said switchboards with both said switching key and said connecting key operated.

12. In a telephone system, an operator attended switchboard, a two conductor trunk having signals, a relay in said trunk, subscribers' lines, automatic switches accessible to said subscribers' lines and accessible to said trunk under control of said operator, means including the two conductors of said trunk for operating said relay to operate one of said signals, a connecting key in said switchboard, means responsive to the operation of said key and including a winding of said relay and one of the conductors of said trunk for operating another of said signals, and

switching means in said trunk, said last means being controllable from said subscribers' lines through any one of said automatic switches, said relay being inoperative, and one of said automatic switches being accessible to the operation of said trunk in response to said first means in case said switching means is operated.

13. In a telephone system, two telephone exchanges, a two way trunk line terminating in said exchanges, a manual switchboard having a signal and a plurality of automatic switches at one of said exchanges, a line switch having outgoing trunks to said automatic switches, means responsive to the closure of said trunk line at the other of said exchanges for operating said signal, and a switch in said trunk line, said signal being disabled and said line switch being operated for seizing one of said automatic switches in response to the closure of said trunk line at said other exchange in case said switch is operated.

14. In a telephone system, an operator attended switchboard having connecting links, a plurality of trunk lines, a plurality of automatic switches having access to said trunk lines through said connecting links, other automatic switches individually accessible to any one of said trunk lines through said connecting links, and switching means in each of said trunk lines manually operable to allow said plurality of automatic switches to have automatic access thereto and to connect individual ones of said other automatic switches to corresponding individual ones of said trunk lines with the switching means in said trunk lines operated.

15. In a telephone system, a trunk line, an operator attended switchboard, operator controlled connecting links therein, a plurality of automatic switches having access to said trunk line through said links, other automatic switches accessible to said trunk line through said links, and switching means in said trunk line operable to allow said plurality of switches to have automatic access thereto and to make one of said other switches automatically accessible to said trunk line responsive to the operation of said switching means.

16. In a telephone system, a trunk line, an operator attended switchboard, a plurality of automatic switches, a plurality of line switches, operator controlled means making said trunk line accessible to said automatic switches for making said automatic switches accessible to said trunk line through said line switches, and switching means in said trunk line operable to make said trunk line automatically accessible to said automatic switches and to make one of said line switches automatically operative with said switching means operated whereby said automatic switches are made accessible to said trunk line by way of said one line switch.

17. In a telephone system, a trunk having a plurality of conductors connecting two switchboards, a line relay and a line signal at each switchboard, automatic switches at one switchboard, means including the trunk conductors for operating the line relay at said one switchboard to operate the line signal thereat, switching means manually operative for making said last mentioned line relay inoperative and an automatic switch operative in response to said first means, and means including the line relay at each switchboard and only one of said conductors for operating the line signal at the other switchboard, said last means effective with or without said switching means operated.

18. In a telephone system, a two conductor trunk connecting two switchboards, automatic switches at one switchboard, a call signal at each switchboard, means including the two conductors of said trunk for operating the call signal at said one switchboard, means for operating the call signal at the other switchboard over a single conductor of said trunk, and means for disabling the call signal at said one switchboard and for making one of said automatic switches operative in response to the operation of said first means.

19. In a telephone system, a trunk circuit having talking conductors, a plural wound relay, a plurality of signals, means responsive to the closure of said talking conductors for energizing two windings of the relay to operate one of said signals, means for energizing one winding of the relay over one of said talking conductors to operate another of said signals, said last means effective to prevent the energization of said relay in response to the closure of said talking conductors.

20. In a telephone system, a two way trunk circuit having talking conductors, a plural wound relay, a plurality of signals, said relay operative in response to the closure of said talking conductors in response to a call over said trunk in one direction to operate one of said signals, means responsive to a call over said trunk in the opposite direction for energizing one winding of the relay over one of said talking conductors to operate another of said signals, means responsive to the answering of said last call for deenergizing said one winding of the relay, said other signal operative in response to the release of said relay, and said first means effective to prevent the energization of said relay in response to the closure of said talking conductors.

21. In a telephone system, a trunk having two conductors, a relay, a line signal, a supervisory signal, means for operating the relay over said two conductors when the trunk is seized in one

manner, said relay effective to operate the line signal, and means for operating the relay over one of said conductors when the trunk is seized in another manner, said relay effective to operate the supervisory signal.

22. In a telephone system, a two conductor trunk, a relay, a call signal, a supervisory signal, means including said relay for operating said call signal in response to the closure of the conductors of said trunk, and means for operating said relay over one conductor of said trunk to operate said supervisory signal.

23. In a telephone system, a two way trunk line connecting two exchanges, a relay and two signals in one exchange, means effective when the trunk is taken for use at the other exchange for operating said relay to operate one of said signals, and means effective when the trunk is taken for use at said one exchange for operating said relay to operate the other of said signals.

24. In a switching system, a two conductor trunk line connecting two switchboards, a line relay and a line signal at each switchboard, means including the trunk line conductors and the line relay at one switchboard for operating the line signal thereat, and means including the line relays at both switchboards and only one of said conductors for operating the line signal at the other switchboard.

KARL L. BURGENER.
